UNITED STATES PATENT OFFICE.

CHARLES S. OLSON, OF DULUTH, MINNESOTA, ASSIGNOR TO HERCULES MANUFACTURING COMPANY, A CORPORATION OF MINNESOTA.

ALARM MECHANISM.

1,036,692.

Specification of Letters Patent. Patented Aug. 27, 1912.

Application filed June 13, 1911. Serial No. 632,901.

To all whom it may concern:

Be it known that I, CHARLES S. OLSON, a citizen of the United States, residing at Duluth, in the county of St. Louis and State of Minnesota, have invented certain new and useful Improvements in Alarm Mechanism; and I do hereby declare the following to be a full, clear, and exact description of the invention, such as will enable others skilled in the art to which it appertains to make and use the same.

My invention relates to alarm apparatus and has for its object the provision of a simple and efficient alarm that may be arranged to guard one or more avenues of attack.

It consists of the constructions, combinations and arrangements of parts hereinafter described and claimed.

20 In the drawings, Figure 1 is a perspective view of my said invention. Fig. 2 is a side elevation of the same, partly broken away, and omitting the hereinafter described cover.

25 In the drawings, 1 is a casing, forming a primary support. Formed on or secured to said support is a stationary segmental rack 2, and a stationary segmental cartridge holder 3, the axis of which cartridge holder is in prolongation of the axis of said segmental rack. Said cartridge holder is provided with one or more radially directed apertures 3^a for receiving cartridges one of which may be placed in each aperture. Pivoted to said support in the line of the axis of said rack and cartridge holder, and extending upward preferably between said rack and cartridge holder is a lever 4 provided with a bracket 4^a of any suitable construction, which bracket carries a housing 4^b extending over said cartridge holder, within which housing is positioned a reciprocatable firing pin 5, adapted to be operated by a spring 6 of any suitable construction or position, preferably inclosed in said housing, said pin is provided with a shoulder 5^a extending out of said housing through a slot 4^c formed in the wall thereof. Rotatably

mounted on said lever, is a gear 7 engaging said rack, and mounted on the axle of said gear and adapted to turn therewith is a ratchet wheel 8. Loosely mounted on the axle of said gear and ratchet wheel is a gear 9, provided upon one face with a pivoted dog 9^a adapted to engage said ratchet wheel and transmit driving power from said ratchet wheel to said gear 9 in one direction of rotation, said dog being adapted to slip on said ratchet wheel during the opposite rotation thereof. One face of said gear 9 is provided with one or more outwardly extending pins, as 9^b, adapted to engage the shoulder on said firing pin and to retract said pin against the action of said spring. Said gear 9 is adapted to mesh with and drive in one direction a pinion 10 carried by said lever, upon the shaft of which pinion 10 is mounted a gear 11 adapted to rotate therewith and to engage and drive a pinion 13 carried by said lever. Upon the shaft of said pinion 13 is mounted a ratchet wheel 14 adapted to turn with said shaft. A dog 15 is pivotally secured to said support and is adapted in operation to engage said ratchet wheel 14 and hold the same against the driving power transmitted from said pinion 7. In order to retract said dog 15 in order to permit of the operation of the alarm, I preferably provide an electro-magnet 16 adapted in operation to attract said dog and withdraw it from engagement with said ratchet wheel 14. Said magnet may be included in a normally open electric circuit comprising binding posts 16^a and 16^b, an electric battery 16^c, circuit wires 16^d and normally open or separated contact plates 16^e and 16^f and a circuit opening or closing switch 16^g. One of said contact plates may be positioned on the side rail of a window sash 17, and the other a little above it on the window casing 18, and so arranged that upon lifting the sash a short distance the contact plates will come into contact with each other and close the circuit. But said dog 15 may if desired be retracted by any suitable and desirable means or mechanism adapted to be operated

by the power against which it is desired to obtain an alarm. Said casing is preferably provided with a cover 19, and a sound and smoke vent 20. In the drawings said cover 5 is shown only in Fig. 1, and said electric circuit is shown only in Fig. 2, except said magnet which is shown in both of said figures. A speed governor, comprising a worm 21 and fan 21^a is mounted on a bracket 22 10 extending from said lever, said worm being adapted to mesh with said ratchet wheel 14. A weight 23 is preferably mounted on the free end of said lever.

In operation, the cartridge holder being 15 filled with blank cartridges, the lever being raised, the dog 15 being engaged with the ratchet 14, the switch 16^a being closed and said window being closed, if, now, a burglar 20 approach and pry open said window the plates 16^a and 16^b come into contact, thus closing the electric circuit and actuating the magnet. Said magnet thereupon attracts 25 said dog 15, disengaging it from said ratchet 14. The lever now swings downward by gravity, carrying the firing pin successively over the cartridges. At the same time the gear 7 is moved by said lever over said rack which causes said gear 7 and its shaft to rotate, thus causing the rotation of the 30 ratchet wheel 8, which by means of the dog 9^a is at such time locked to the gear 9 which is thus caused to rotate so as to successively and at regular intervals bring the pins 9^b 35 into lifting contact with the shoulder on the firing pin. As the gear 9 continues to rotate, the pins 9^b slip from beneath the shoulder on the raised firing pin, which is then operated against the cartridge temporarily beneath it so as to fire the same and thereby 40 give alarm. After the lever has dropped, the device may be re-set by breaking the electric circuit, raising the lever, engaging the dog 15 and re-filling the cartridge holder.

45 What I claim is:—

1. In an alarm mechanism, the combination with a suitable support of a stationary segmental rack, a stationary segmental cartridge-holder having its axis coincident with 50 the axis of said rack; a pivoted lever having its axis coincident with the axes of said rack and holder, a reciprocatable firing pin carried by said lever over the periphery of said cartridge holder, a gear carried by said 55 lever in mesh with said rack, means carried by said lever and adapted to be actuated by said gear in co-operation with said lever and rack to retract said firing pin, and means for actuating said firing pin after the same 60 has been retracted.

2. In an alarm mechanism, the combination with a suitable support, of a stationary segmental rack, a stationary segmental cartridge-holder having its axis coincident

with the axis of said rack, said cartridge- 65 holder having radially directed cartridge chambers formed in its periphery, a pivoted lever having its axis coincident with the axes of said rack and cartridge holder, a housing mounted on said lever and positioned over said cartridge holder, a reciprocatable firing pin positioned in said housing, means for actuating said firing pin, and means co-operating with said lever and rack for retracting said firing pin. 70 75

3. In an alarm mechanism, the combination with a suitable support, of a stationary rack, a stationary cartridge holder containing a cartridge chamber, a pivoted lever, means carried by said lever for firing a cartridge placed in said chamber, means co-operating with said rack and lever for retracting said firing means, means mounted in part on said lever for preventing the movement of said lever or the operation of said firing 80 means, and means for retracting said preventive means.

4. In an alarm mechanism, the combination with a casing forming a suitable support, of a stationary segmental rack positioned in said casing, a stationary segmental cartridge holder positioned in said casing having its axis coincident with the axis of said rack, a pivoted lever extending into said casing and pivoted therein having its axis 90 coincident with the axes of said rack and holder, a gear mounted on said lever and engaging said rack and adapted to be actuated by said rack in co-operation with said lever when said lever swings in operative 95 direction on its pivot, a firing pin carried over said cartridge holder by said lever, said firing pin being provided with a shoulder adapted to be engaged by retracting means, means for actuating said firing pin, a ratchet wheel mounted on the shaft of said gear wheel and adapted to turn therewith, a retracting wheel loosely mounted on the shaft of said gear wheel and provided with 100 retracting pins adapted successively to engage said shoulder on said firing pin to retract said pin, a dog mounted on said loose wheel and adapted to be engaged by said ratchet wheel and to rotate said loose wheel in operative direction, means for temporarily preventing the operation of said 105 wheels, and means for governing the speed of rotating said wheels.

5. In an alarm mechanism, the combination with a suitable support of a series of stationary cartridge chambers, a stationary rack, an automatically movable firing-pin carriage, a firing pin adapted to be carried thereby into firing position with respect to each of said chambers successively, retracting means mounted on said carriage and engaging said rack and adapted in co-operation with said carriage and rack to retract 110 115 120 125

said firing pin during the passage thereof from operative position with respect to one of said chambers to operative position with respect to a succeeding one of said chambers, 5 means for temporarily preventing the movement of said carriage, and means for retracting said preventive means.

In testimony whereof I hereunto affix my signature, in presence of two witnesses.

CHARLES S. OLSON.
